COLLAPSIBLE STRETCHER

Lester L. Bauer, Toledo, Ohio, assignor to Gendron Wheel Company, Perrysburg, Ohio, a corporation of Ohio

Application March 7, 1955, Serial No. 492,555

4 Claims. (Cl. 5—81)

This invention relates to collapsible stretchers and its objects are to produce a structure of this character which is positively secured or fastened in its extended position of use; and to enable the stretcher to be retained in its collapsed position by its own weight and without the use of separate securing means.

A further object is to simplify and improve the latching means, rendering the same positive in action and providing for the free and unhampered movement from use to collapsed position.

A still further object resides in the construction and arrangement of parts which are such as to occupy a minimum amount of space in collapsed position and automatically to retain same in such position and without interfering with the simple movement of the parts to position of use.

Other objects and advantages of the invention will hereinafter appear and for purposes of illustration but not of limitation, an embodiment of the invention is shown on the accompanying drawings in which:

Figure 1 is a side elevation of the collapsible stretcher in position of use;

Figure 2 is an end elevation of the stretcher;

Figure 3 is a side elevation of the stretcher in collapsed condition;

Figure 4 is an enlarged fragmentary side elevation of the central portion of the stretcher showing the latch mechanism and associated parts;

Figure 5 is a fragmentary transverse sectional view of one side portion of the stretcher showing the latching mechanism and associated parts, the stretcher being in position of use;

Figure 6 is a view similar to Figure 5 showing the position of the parts during the movement from position of use to collapsed position; and

Figure 7 is an enlarged transverse sectional view on the line 7—7 of Figure 5.

The illustrated embodiment of the invention comprises a collapsible stretcher for use in hospitals, doctors' offices and the like, which can be readily collapsed so as to occupy a relatively small space. As shown, the stretcher comprises two flat panel sections 10 which, when in aligned horizontal position, as indicated in Figure 1, are in position of use. Depending from the underside of each of the panel sections 10 at an intermediate point are brackets 11, which are arranged in pairs, one being disposed adjacent each side edge. Extending through each pair of brackets 11 is a transverse rod 11a, over which fits a spacer tube 11b. The ends of each spacer tube 11b abuts against the inner sides of the respective brackets 11. Suitably fixed to each spacer tube 11b and extending across to a bracket 11c fixed to and depending from the opposite panel section 10 is a helical coil spring 11d. Thus the two springs 11d in a sense overlap each other.

On the outer side of each bracket 11 and pivoted on the extended end portion of the respective rod 11a is a vertical depending leg 12 which terminates in a downwardly and outwardly curved end portion 13. Rigid with

2

the end of the curved end portion 13 is a vertically disposed sleeve 14 and each pair of sleeves 14 is connected by a transverse brace 15. Mounted for pivotal movement in each of the sleeves 14 is a caster unit 16, which can swivel about a vertical axis to facilitate the ambulatory movement of the stretcher.

Pivoted at 18 to the lower end of each of the vertical legs 12 and projecting inwardly therefrom is a brace rod 17.

10 The adjacent ends of the brace rods 17 are flattened for a portion of their length as indicated at 19 and the extreme rod ends overlap each other and are pivotally mounted on a transverse rod 20, thereby enabling the rods 17 to pivot around transverse axes. Particularly as shown in Figures 5 and 6, the rods 20 is enclosed by a spacer tube 21 which abuts at its ends against the adjacent flattened end portions 19 of the brace rods 17 at opposite sides of the stretcher.

Also pivoting about the transverse rod 20 and abutting 20 against the outermost of the flattened ends 19 of brace rods 17 are flattened end portions 23 respectively of vertically disposed arms 22. It will be understood that an arm 22 is disposed on each side of the stretcher and both arms are pivotally mounted upon the rod 20. The upper ends of the arms 22 are pivoted to a transverse rod 24a which is connected to downwardly and inwardly inclined brackets 24 fixed to the adjacent ends respectively of the panel sections 10. Enclosing the transverse rod 24a is a spacer tube 24b which abuts at its opposite ends against the inner side of the arms 22, thereby retaining these parts against lateral movement.

Slidable vertically on each of the upright arms 22 is an elongate sleeve 25 which bears against the brackets 24 when the stretcher is in use. Each sleeve 25 has fixed 35 to its inner side adjacent its lower end a cross-arm 26 which projects equally upon opposite sides of the sleeve and is arranged generally parallel to the flat panel sections 10 when the latter are disposed in horizontal position of use. Pivoted to the opposite ends of each cross-arm 26 are downwardly and outwardly inclined links 27, the lower ends of which are pivoted to a respective brace rod 17 substantially midway of its length.

On the outer side of one of the vertically disposed arms 22 is an elongate leaf spring 28 which is of slightly less 45 length than that of the arm. The lower end of the spring 28 is fixed to the arm 22 adjacent the flattened portion 23 by a pair of attaching screws 29, the remainder of the spring being free for flexing movement. The upper end portion of the leaf spring 28 overlaps a portion of the sleeve 25 when the latter is in its uppermost position. Fixed to the upper end of the spring is a post 30 which extends outwardly from the spring and provides an actuating handle. Above the handle post 30 and fixed to the end of the spring 28 is a substantially C-shaped guard 31 55 which is adapted to hook around the sleeve 25 or the tube 22 for restraining the outward flexing movement of the spring.

Fixed to the spring 28 on the inner side thereof and in alignment with the handle post 30 is a pin 32 which is 60 adapted to enter registering holes 33 and 34 in the sleeve 25 and tube 22 respectively for locking the stretcher in its position of use. Additionally, a pin 35 fixed to the lower end portion of the sleeve 25 and projecting toward the spring 28 is adapted to enter a hole 36 in the spring as indicated on Figure 5, thereby to aid in securing the stretcher in position of use. It will be observed, particularly on Figures 5 and 6, that the upper portion of the leaf spring 28 is straight as indicated at 37, this portion being substantially parallel and juxtaposed to the arm 22. Approximately midway of the length of the spring is an outwardly inclined portion 38 which merges with a lower spring por-

tion 39 which is also approximately parallel to the arm 22 but spaced at greater distances outwardly therefrom.

In operation, when it is desired to collapse the stretcher from its position of use, the handle post 30 is grasped and pulled outwardly in order to release the pins 32 and 35 from their respective holes and thereby releasing the parts from their secured position, such outward movement of the handle post being limited by the guard 31. Then by lifting upwardly on the post, it will be manifest that the arms 22 and associated parts are lifted upwardly, pulling upwardly on the horizontal brace rods 17. At the same time the sleeve 25 tends to move relatively downward on the respective arm 22, due to the articulation of parts. As the arm 22 moves upwardly, the pin 35 on the inner face of the sleeve 25 rides along the spring portion 37 and thereby holds the pin 32 from entering the hole 34 in the tube 22 after such hole has been uncovered by the relative movement of the parts. The continuing collapsing movement of the stretcher enables the pin 35 to relatively ride along the cam surface 38 and eventually find its position along the relatively straight spring portion 39, enabling the spring 28 to move of its own resiliency closer to the arm 22. It will thus be seen that the latching mechanism is automatic in fastening the parts in a position of use and when the parts are moved from position of use toward collapsed position, the leaf spring 28 is positively held in an outward flexed position to militate against the pin 32 entering the hole 34 and locking the parts.

One important feature of the above structure is the arrangement which enables the parts to be held in collapsed position and automatically retain the parts in such position until such time as the stretcher is positively moved from that position to the position of use. This is achieved by providing the flattened ends 19 of the horizontal braces 17 of a sufficient length so that when the pairs of pivotally connected braces 17 are swung upwardly to the collapsed position of the stretcher, sufficient movement is allowed to form a relatively small angle therebetween and such as to enable the adjacent pairs of legs 12 to tilt inwardly at their upper ends toward each other. Thus in effect, the legs 12 are off-center since they incline toward each other at their upper ends, the weight of the flat panel sections 10 bearing against the parts causing the stretcher to remain in collapsed condition by its own weight. Manifestly this is of advantage because after the stretcher is collapsed and moved into storage, then no further concern need be given it so far as its moving of its own accord to its extended position. For the stretcher to resume its extended position, a positive force is necessary, such as lifting the outer ends of the panel sections 10. By virtue of this structure, a smaller space is occupied by the stretcher when in its collapsed position. Manifestly if the flat portions 19 were shortened causing a greater angular disposition of the legs, not only would greater storage space be required, but the stretcher would automatically open up to its extended position due to the disposition of the weight of the parts unless restraining means were used.

Numerous changes in details of construction, arrangement and operation may be effected without departing from the spirit of the invention, especially as defined in the appended claims.

What I claim is:

1. A collapsible stretcher having a pair of articulated assemblies movable between a position of use and a collapsed position, each assembly comprising a body-supporting panel section, supporting leg elements pivoted to the outer end position of the panel section, brace arm members pivoted to the lower portion of said leg elements respectively, means for pivotally connecting the adjacent ends of said arm members, said connecting means including vertical post members, and pivotal connections between the upper ends of said post members and the adjacent ends of said panel sections respectively, a sleeve slidable on one of said post members, diagonal braces pivoted to opposite

sides of said sleeve respectively at one end and an intermediate portion of said brace arm members respectively, the improvement which comprises an elongate spring arm fixed at one end to said post with its upper end overlapping said sleeve, pins rigid with said sleeve and spring arm and extending in opposite directions, said spring arm having a hole to receive the sleeve carried pin, there being holes in the sleeve and post adapted to register when the stretcher is in position of use for reception of the spring arm carried pin, the arrangement being such that in the collapsing movement of the parts the spring arm engages the sleeve carried pin thereby to hold the spring arm carried pin from entering the hole in the post, and a handle rigid with said spring arm for moving the parts to collapse position.

15 2. A collapsible stretcher having a pair of articulated assemblies movable between a position of use and a collapsed position, each assembly comprising a body-supporting panel section, supporting leg elements pivoted to the outer end position of the panel section, brace arm members pivoted to the lower portion of said leg elements respectively, means for pivotally connecting the adjacent ends of said arm members, said connecting means including vertical post members, and pivotal connections between the upper ends of said post members and the adjacent ends 20 of said panel sections respectively, a sleeve slidable on one of said post members, diagonal braces pivoted to opposite sides of said sleeve respectively at one end and an intermediate portion of said brace arm members respectively, the improvement which comprises an elongate spring arm fixed at one end to said post with its upper end overlapping said sleeve, pins rigid with said sleeve and spring arm and extending in opposite directions, said spring arm having a hole to receive the sleeve carried pin, there being holes in the sleeve and post adapted to register when the stretcher is in position of use for reception of the spring arm carried pin, the arrangement being such that in the collapsing movement of the parts the spring arm engages the sleeve carried pin thereby to hold the spring arm carried pin from entering the hole in the post, an offset portion of the spring arm at the lower region thereof to accommodate the sleeve pin and enable the spring to lie closely to the post in collapsed position of the parts, and a handle rigid with said spring arm for moving the parts to collapsed position.

30 3. A collapsible stretcher having a pair of articulated assemblies movable between a position of use and a collapsed position, each assembly comprising a body-supporting panel section, supporting leg elements pivoted to the outer end position of the panel section, brace arm members pivoted to the lower portion of said leg elements respectively, means for pivotally connecting the adjacent ends of said arm members, said connecting means including vertical post members, and pivotal connections between the upper ends of said post members and the adjacent ends of said panel sections respectively, a sleeve slidable on one of said post members, diagonal braces pivoted to opposite sides of said sleeve respectively at one end and an intermediate portion of said brace arm members respectively, the improvement which comprises means on adjacent end portions of said brace arm members enabling same to overlap sufficiently when the stretcher is in collapsed position as to be over center so that the structure will be automatically retained in such position.

35 4. A collapsible stretcher having a pair of articulated assemblies movable between a position of use and a collapsed position, each assembly comprising a body-supporting panel section, supporting leg elements pivoted to the outer end position of the panel section, brace arm members pivoted to the lower portion of said leg elements respectively, means for pivotally connecting the adjacent ends of said arm members, said connecting means including vertical post members, and pivotal connections between the upper ends of said post members and the adjacent ends of said panel sections respectively, a sleeve

slidable on one of said post members, diagonal braces pivoted to opposite sides of said sleeve respectively at one end and an intermediate portion of said brace arm members respectively, the improvement which comprises flattened end portions on the adjacent end of said brace arms enabling same to overlap sufficiently when the stretcher is in collapsed position as to be over center so that the structure will be automatically retained in such position.
